J. B. Atwater

UNITED STATES PATENT OFFICE.

J. B. ATWATER, OF BERLIN, WISCONSIN.

CAR-COUPING.

Specification of Letters Patent No. 22,776, dated February 1, 1859.

To all whom it may concern:

Be it known that I, J. B. ATWATER, of Berlin, in the county of Green Lake and State of Wisconsin, have invented certain new and useful Improvements in Railroad-Car Couplers; and I do hereby declare that the following is a full, clear, and exact description of the same, reference being had to the accompanying drawings and to the 10 letters of reference marked thereon.

The nature of my invention consists in arranging and combining together the several parts which will be hereinafter described.

In the annexed drawings making a part 15 of this specification, A represents the body of the coupling.

B represents the front or face which is provided with a square hole into which the link passes in order that it may receive the 20 pin.

C is a rod, which is provided at one end with a crank,—the other end is secured in suitable bearings under the body of the coupling and is provided near its extremity 25 with a tumbler c, said tumbler playing through a slot in the underside of the body of the coupler.

E, represents a lever which has its fulcrum at α in the upright F. One end of this 30 lever connects with the pin d, and the other end is connected by means of connecting piece D, with the crank on rod C.

σ is a footpiece on lever E. i is a door, or, platform, which is hinged 35 at one end to the body of the coupler the other end falling freely of its own gravity on the link, serves to keep it in proper position.

m, n, represent two friction rollers which 40 I place in front of the pin so that when drawing up a heavy grade the pin may be readily disconnected by pressing upon lever E.

It will be readily perceived that this cou-

pler is a self connector. When it is desired 45 to connect two cars, the several parts seen in Fig. 3 stand in the position seen in that figure. The tumbler c, is erect; and the pin is raised in order that the link may pass in. When the link e, strikes the tumbler it is 50 thrown down in the position seen in Fig. 1, as it falls it turns the rod C, which by means of its crank, operates upon the piece D, and it in turn upon the lever E, which serves to throw the pin d, down into the link and thus 55 secures it.

The link and pin do not differ materially from those in ordinary use, and when the cars are drawing are no more liable to separate. 60

When it is desired to uncouple a car, the pin is very easily thrown up, by pressing with the foot upon the foot piece σ , of lever E,—as the pin rises the tumbler c, is also elevated and at the same time the pin leaves the link the tumbler shoves it out, so that it 65 can not remain under the pin in position for connecting.

I do not claim the employment of any of the parts of this coupler to be new, uncombined and differently arranged, as I am aware that the pin has been thrown down in other couplers by means of the link, pressing against such parts as affect it,—hence 70 I disclaim all other modes of effecting the 75 result herein attained, confining myself to the arrangement herein specified to wit:

The arrangement of the tumbler c, rod C, connecting piece D, lever E, which is provided with a foot piece, σ , pin d, rollers m, 80 n, and door or platform i, the whole being combined and operated in the manner and for the purpose herein specified.

J. B. ATWATER.
